UNITED STATES PATENT OFFICE

2,587,207

THERAPEUTIC VIBRATOR

Dorothy M. Peterson, San Francisco, Calif.

Application February 3, 1948, Serial No. 6,037

5 Claims. (Cl. 128—33)

1

This invention relates to therapeutic vibrators and more particularly to a vibrant mounting for oscillating motors.

Among the objects of the invention is the provision of a controlled motor base for modulating the oscillation of off-balance motors of therapeutic apparatus in this class.

Another object is the provision of means for adjusting the vibratory range of the vibrator to a rate desired by the user.

A further object is to cushion the contacts between vibratory parts of the apparatus to dampen or minimize the noise of operation.

Other objects and advantages will appear as the description proceeds. In the specification and the accompanying drawings the invention is disclosed in its preferred form. But it is to be understood that it is not limited to this form; because it may be embodied in modifications within the spirit of the invention as defined in the claims following the description.

In the one sheet of drawings:

Fig. 1 is a side elevation of a motor mounting assembly constructed in accordance with this invention.

Fig. 2 is a plan view from below of the same.

Fig. 3 is a side elevation of a conventional chair having this invention installed beneath the seat, portions of the seat upholstery being broken away.

Fig. 4 is a similar view of an oscillating unit partially broken away in vertical section with the motor mounting assembly installed therein.

Fig. 5 is a modification in a side elevation of the modulator board mounted directly upon the base.

In detail the structure shown in Fig. 1 comprises the base board 1 with its four corners attached to the chair bottom X by screws such as 2, with the interposed rubber discs such as 3 interposed between the base board 1 and the underside of the chair bottom X.

The motor unit 4 is attached to the "modulator board" 5 by the bolts such as 6 passing through the base board 1, the interposed rubber buttons 7, the flange 8 of the motor base and secured by the nuts 9. There are preferably four such bolts 6 and buttons 7 for firmly mounting the motor 4 on the base board 1 with the interposed modulator board.

The carriage step type damper bolt 10 passing through the base board 1 and the modulator board 5 is anchored against turning in the base board. The adjusting wing nut 11 is threaded on the damper bolt and bears against the rubber cushion 12 interposed between the modulator board and the wing nut.

In the present assembly the induction mo-

2

tor 4 is a single phase shaded pole type but may be any suitable motive means. The protruding shaft ends 13 and 14 of the motor have the weights 15 and 16 eccentrically fixed thereon, respectively. These eccentric weights throw the motor out of balance and cause it to oscillate transversely to the axis of the motor shaft which is in line with the length of the modulator board 5.

10 The resilient rubber buttons 7 permit the modulator board to vibrate up and down relative to the plane of the base board 1 under adjustable control of the damper bolt assembly 10—12. This form of directional oscillation should not be confused with the diffusive stimulating effect of vibrating massage devices manually applied locally.

The chair shown in Fig. 3 has the tubular frame 17, the thinly padded seat 18 and the curved back 19 of conventional construction and is preferred to the ordinary chair because of its simplicity and sturdy construction, but the present invention may be installed on reclining seats, beds and any other form of human body support. The oscillating assembly is attached beneath the chair seat board X as shown in Fig. 1.

This invention operates substantially as follows: When the wing nut 11 is backed off it frees the modulator board from control. The eccentric weights 15 and 16 set up an off center load on the motor 4 that perceptibly slows down its revolutions per minute to which the modulator board 5 harmoniously reciprocates. Tightening the wing nut 11 adds an extra load to the eccentric weights and further slows down the motor speed and increases the amount of oscillation throughout the structure to which the invention is applied, as in Fig. 3.

40 A user sitting upright on the cushion 18 and leaning back against the curved back 19 is gently shaken throughout the whole mass of his body from the soles of the feet to the scalp of the head. This imparts a soothing relaxing effect upon the body. Adjustment of the wing nut 11 enables the user to adjust the apparatus to a desired rate of vibratory oscillation.

In Fig. 4, the same general structure of the invention is similarly installed within the oscillating unit comprising the bottom board X' enclosed by the cover Y and having a padded, upholstered leatherette covering Z. This convenient unit may be applied to any region of the human body for local treatment, such as the feet, spinal region or the limbs.

It is desirable that the base board 1 be firmly attached to the chair bottom X. This base board is more of a convenience in applying the

invention to a chair or the like and may in some instances be omitted by attaching the modulator board assembly directly to the bottom X of the chair.

In the modification shown in Fig. 5, the modulator board 5x is attached directly to the chair seat Xx by the wood screws 6x passing through the motor base 8x, and the resilient buttons 7x and are screwed into the chair seat Xx. The damper bolt 10x has the head 11x by which it is screwed into the chair seat board Xx and bears against the cushion 12x for adjusting the modulator board as described.

In practice the base board 1 as shown is about one foot long with the rest of the assembly in proportion but size is a matter of choice in meeting special requirements. The base board 1 and the modulator board 5 are preferably made of plywood because of its strength and low resonant qualities, but these parts may be composed of metal plates, plastic sheets or other suitable materials.

Having fully described this invention and its mode of operation, what I claim and desire to secure by Letters Patent is:

1. A therapeutic apparatus comprising a base member, a vibratable modulator member for providing control of rate of vibration, an off-balance motor mounted on said modulator member, means securing said modulator member to said base member at one portion of said modulator member, resilient means interposed between the inner side of said modulator member and said base member at said one portion, an opposite portion of said modulator member being spaced from said base member, adjustable connecting means at said opposite portion and connected to said base member, said connecting means having an adjustable member, and resilient means associated with said adjustable member and said modulator member whereby said adjustable connecting means and said latter resilient means provide a controllable damper for said modulator member.

2. A therapeutic apparatus comprising a base member, a vibratable modulator member for providing control of rate of vibration, means securing said modulator member to said base member at one portion of said modulator member, an off-balance motor mounted on said modulator member and secured thereto by said securing means, resilient means interposed between the inner side of said modulator member and said base member at said one portion, an opposite portion of said modulator member being spaced from said base member, adjustable connecting means at said opposite portion and connected to said base member, said connecting means having an adjustable member, and resilient means associated with said adjustable member and said modulator member whereby said adjustable connecting means and said latter resilient means provide a controllable damper for said modulator member.

3. A therapeutic apparatus in the form of a unitary attachment adapted to be secured to a human body supporting object and comprising a base member adapted to be secured to said object, a vibratable modulator member for providing control of rate of vibration spaced from said base member, an off-balance motor mounted on said modulator member, means securing said modulator member to said base member at one portion of said modulator member, resilient means interposed between the inner side of said

modulator member and said base member at said one portion, an opposite portion of said modulator member being spaced from said base member, adjustable connecting means at said opposite portion and connected to said base member, said connecting means having an adjustable member at the outer side of said modulator member, and resilient means interposed between said adjustable member and said outer side of said modulator member whereby said adjustable connecting means and said latter resilient means provide a controllable damper for said modulator member.

4. A therapeutic apparatus in the form of a unitary attachment adapted to be secured to a human body supporting object and comprising a base member adapted to be secured to said object, a vibratable modulator member for providing control of rate of vibration spaced from said base member, securing means comprising bolts passing through said base member and through said modulator member adjacent one end of said modulator member, resilient means adjacent said bolts interposed between the inner side of said modulator member and said base member, an off-balance motor secured to said modulator member by said securing means, adjustable connecting means comprising a bolt passing through said base member and through said modulator member adjacent an opposite end of said modulator member and connected to said base member, said bolt having an adjustable member at the outer side of said modulator member, and resilient means interposed between said adjustable member and said outer side of said modulator member whereby said adjustable connecting means and said latter resilient means provide a controllable damper for said modulator member.

40 5. A therapeutic apparatus comprising a base member, an elongated substantially flat modulator member for providing control of rate of vibration spaced from and extending substantially parallel to said base member, an off-balance motor mounted on said modulator member adjacent one end thereof, means securing said modulator member to said base member at said end of said modulator member, resilient means interposed between the inner side of said modulator member and said base member at said end, adjustable connecting means at the opposite end of said modulator member and connected to said base member, said connecting means having an adjustable member, and resilient means associated with said adjustable member and said modulator member whereby said adjustable connecting means and said latter resilient means provide a controllable damper for said modulator member.
